UNITED STATES PATENT OFFICE.

CLARENCE C. LONGARD, OF HALIFAX, NOVA SCOTIA, CANADA.

INTERNAL-COMBUSTION ENGINE.

1,093,709.

Specification of Letters Patent. Patented Apr. 21, 1914.

Application filed February 24, 1913. Serial No. 750,319.

To all whom it may concern:

Be it known that I, CLARENCE C. LONGARD, a subject of the King of Great Britain, residing at Halifax, in the Province of Nova Scotia and Dominion of Canada, have invented new and useful Improvements in Internal-Combustion Engines, of which the following is a specification.

My present invention pertains to internal combustion engines, and contemplates the provision of means for assuring the explosion chamber being fully occupied by highly explosive mixture precedent to each explosion and for otherwise increasing the efficiency of the engine.

Other objects and advantageous features of the invention will be fully understood from the following description and claim when the same are read in connection with the drawing, accompanying and forming part of this specification, in which the figure is a vertical diametrical section of an internal combustion engine constructed in accordance with my invention.

In common with internal combustion engines extant, my novel engine comprises a cylinder and a piston; the cylinder being divided by the piston into an explosion chamber 1 and a compression chamber 2.

The explosion chamber is provided with a spark plug 3 or any other suitable ignition device, and is also provided with an exhaust port 4 and an explosive-mixture inlet port 5; the exhaust port being arranged so as to be uncovered by the piston during the completion of the outward traverse thereof, and the port 5 being located in the outer end of the chamber and being controlled by an outwardly seating valve 6 equipped with a spring 7.

Communicating with the inner part of the compression chamber is a port 8, designed to be connected with a suitable source of explosive-mixture supply. Communicating

with the compression chamber 2, preferably at a point diametrically opposite to and in about the same plane as the port 8, is an eduction port 9, controlled by an outwardly-opening valve 10, equipped with a spring 11.

The port 9 opens into an explosive-mixture container 12 separated by a single wall from the compression chamber 2 and which preferably surrounds said compression chamber as shown. Intermediate the inner end of the container 12 and the port 5 is a by-pass conduit 13 which is formed through the wa-

ter jacket 14 in the wall of the cylinder and is separated by a single wall from the explosion chamber in the manner illustrated. By virtue of this the explosive mixture is heated to a considerable extent before it enters the explosion chamber, as is desirable.

In the practical operation of my novel engine, the explosive mixture commences to enter the chamber 1 through port 5 as the piston is moving outwardly over the exhaust port 4, and consequently the said mixture is enabled to accelerate the discharge of the products of the previous explosion and occupy the outer portion of the explosion chamber. On the subsequent inward traverse of the piston, the inflow of explosive mixture through port 5 continues until the compression closes the valve 6. On the subsequent outward movement of the piston, the valve 10 will be held closed by the suction during the drawing of the explosive mixture into the chamber 2, but notwithstanding this the explosive mixture previously stored under pressure in the container 12 will pass through the conduit 13 and port 5 into the explosion chamber and accelerate the passage of products of combustion through the port 4. It will also be manifest that the storing of the explosive mixture in the container 12 and conduit 13 will contribute to the heating of the explosive mixture precedent to the passage of the same into the explosion chamber. From this it follows that the container 12 constitutes an important feature of my invention, and at this point I would have it understood that while I prefer to arrange said container around and immediately adjacent the compression chamber, I do not desire to be understood as confining myself to such arrangement, since without involving departure from the scope of my claimed invention, the container 12 may be separate from the cylinder.

The cylinder may be made in sections or may be cast in one piece or otherwise formed without involving departure from the scope of my claimed invention.

Having described my invention, what I claim and desire to secure by Letters-Patent, is:

The herein described internal combustion engine, comprising a cylinder and a piston; the cylinder being divided by the piston into an explosion chamber and a compression chamber and having an inlet port for

explosive mixture communicating with the compression chamber and also having a container surrounding and separated by a single wall from the compression chamber and connected through a port therewith and further having an inlet port and an exhaust port communicating with the explosion chamber, a water jacket around the explosion chamber, and a by-pass passage 10 extending through said water jacket and connecting the container and the inlet port of the explosion chamber and separated by a single wall from said chamber; an inwardly seating valve controlling the port 15 between the compression chamber and the container and constructed and arranged to be opened by the outward traverse of the piston and closed by the outward traverse

thereof, and an outwardly seating valve controlling the inlet port of the explosion 20 chamber and constructed and arranged to be opened by the outward traverse of the piston and closed by the inward traverse thereof, the exhaust port being relatively arranged to be opened by the piston as the 25 latter approaches the end of its outward traverse, all substantially as and for the purpose set forth.

In testimony whereof I have hereunto set my hand in presence of two subscribing witnesses. 30

CLARENCE C. LONGARD.
